ASSIGNORS TO FLANAGAN COMPANY, OF TULSA, OKLAHOMA, A CORPORATION OF
OKLAHOMA.

BURNER FOR GAS AND OIL.

1,230,883.

Specification of Letters Patent. Patented June 26, 1917.

Application filed September 23, 1916. Serial No. 121,759.

To all whom it may concern:

Be it known that we, THOMAS J. FLANAGAN and MICHAEL J. FLANAGAN, citizens of the United States, residing at Tulsa, in the county of Tulsa and State of Oklahoma, have invented certain new and useful Improvements in Burners for Gas and Oil, of which the following is a specification, reference being had therein to the accompanying drawing.

This invention relates to improvements in burners of that type more particularly designed for use in connection with natural gas and oil, although useful for either natural gas or oil to be used alone, as will hereinafter appear.

In the accompanying drawings we have illustrated the preferred embodiment of the invention, and the improved details of construction and arrangement of parts thereof will be apparent from the specific description hereinafter contained when read in connection with such drawings.

In the drawings:

25 Figure 1 is a longitudinal sectional view of the burner.

Fig. 2 is an elevation of the same; and, Fig. 3 is an end view.

Referring more specifically to the drawings wherein like reference letters designate corresponding parts, in the several views A represents an outer casing of relatively large size terminating at one end in the integral reduced nozzle portion B and at the other end in the flanged bearing C. Near the bearing end of the member A and projecting from the top thereof is an integral valve chamber D provided with a valve seat E bordering a port F communicating with the chamber G on the inside of the member A.

H is a valve bonnet threaded into the upper end of the valve chamber D, the same adjustably supporting the threaded stem J of the valve K having the usual operating hand wheel L. The valve chamber D has a series of ports or openings for air, around the side thereof as shown at M disposed to be above the valve K when on its seat E, but to afford communication from the exterior 45 of the device to the chambers F and G when the valve is raised from its seat to open the same. Inserted in the bearing portion C of the member A and held against rotation with reference to the latter by a flanged end

55 O detachably bolted to the bearing flange as at P is a sleeve N reduced in diameter for the major portion of its length to assist in connection with the member A in providing the air chamber G to which we have alluded, the inner end of this sleeve carrying a detachable section or tube Q terminating in a restricted outlet R positioned somewhat short of the end of the nozzle B.

The sleeve N constitutes the immediate oil and gas chamber T adapted to receive its supply, dependent upon conditions and desired service, from either or both of the sources (not necessary to be illustrated herein) feeding through the gas nipple S or oil nipple S' sleeved through the outer casing A and threaded through the sleeve N to discharge into the interior of the latter.

U is a steam pipe arranged within the oil and gas chamber T carried by a knuckle V threaded into the outer end of the sleeve N and communicating with any suitable source of steam supply as through a nipple W, the end of the knuckle being normally closed through the medium of a detachable plug X adapted to afford access to the interior of 75 the steam pipe for the purpose of cleaning, etc.

The nipple W may be disposed at any desired angle with reference to the device by merely adjusting the knuckle in a rotary direction enabled by its threaded mounting and the squaring of the exterior thereof as at v for the accommodation of a wrench or similar tool.

The end of the steam pipe U terminates 90 considerably short of the end of the sleeve N, or more specifically at a point adjacent to the oil and gas nipples S and S', and in this end of the steam pipe is removably inserted a suitable apertured plug Y constituting a jet nozzle discharging into the chamber T in axial alignment with the oil and gas tube Q. The outer surface of the steam jet nozzle Y flares toward the end of the same and toward the inner wall of the sleeve N as at Z to afford an annular reduced passage around the nozzle Y within the chamber T of the sleeve N.

In using the device the air valve is adjusted to admit the desired proportion of air to mingle with the mixture discharged into the chamber near the end of the nozzle B; the steam through a suitable valve (not

shown) is admitted through the steam pipe and discharged through the jet nozzle Y into the chambers T and Q, which will create a suction facilitating the feeding of the oil or 5 gas or both into the sleeve N, whence it flows outwardly in a cylindrical film formation around the enlarging end of the steam jet nozzle into the mixing chamber T beyond the nozzle and into the tube Q where the oil, 10 gas and steam effect an intimate mixture which, emitted through the contracted end R of the tube Q, will there mix with the air and tend to suck the air into and through the device. Where oil only is used the gas 15 is cut off at the nipple S' through any approved valve mechanism (not shown), and where gas only is used the supply to the oil nipple S is similarly cut off. When it is desired to enrich the natural gas when in a 20 weak or impoverished state, both oil and gas are admitted in appropriate proportions through the nipples S and S', as will be obvious.

While we have herein disclosed a particular embodiment of the invention it will 25 be apparent to persons skilled in the art that changes and alterations may be made therein, and still other embodiments resorted to without departing from the spirit of the 30 invention, as found within the scope of the hereto appended claims.

Having thus described the invention, what is claimed is:

1. In a device of the character described, 35 a combined oil and gas burner comprising an air chamber, a gas and oil chamber having independent inlets for oil, gas, or both, and a steam supply nozzle, all arranged to effect an intimate mixture of the oil, gas, 40 steam and air prior to discharge from the device, the steam supply nozzle being arranged within the gas and oil chamber to discharge beyond the inlets for the oil and gas, and said nozzle terminating in a jet device flaring outwardly to form a restricted 45 passage for the oil and gas to the mixing area beyond said jet device.
2. In a device of the character described, 50 an outer member having a controlled inlet leading to an air chamber therewithin, a member constituting a gas and oil chamber within said air chamber arranged to discharge into a space within the device for 55 admixture of the oil, gas and air, separate inlets for oil and gas passed through the outer member and into the member forming the gas and oil chamber so as to discharge 60 into the latter, and a steam supply nozzle 65 within the gas and oil chamber adapted to discharge at a point in immediate proximity to the oil and gas inlets to facilitate the feeding of the oil and gas and to effect admixture of the oil, gas, and steam within the device.
3. In a device of the character described, 70 a combined oil and gas burner comprising an outer member having a controlled inlet leading to an air chamber therewithin, a member constituting a gas and oil chamber within said air chamber arranged to discharge into a space within the device for admixture of the oil, gas and air, separate inlets for oil and gas passed through the outer member and into the member forming the gas and oil chamber so as to discharge 75 into the latter, and a steam supply nozzle within the gas and oil chamber adapted to discharge at a point to effect admixture of the oil, gas and steam within the device in a space prior to the admission of the air to the mixture of oil, gas and steam.
4. In a device of the character described, 80 a combined oil and gas burner comprising an outer member having a controlled inlet leading to an air chamber therewithin, a member constituting a gas and oil chamber within said air chamber arranged to discharge into a space within the device for admixture of the oil, gas and air, separate inlets for oil and gas passed through the outer member and into the member forming the gas and oil chamber so as to discharge 85 into the latter, and a steam supply nozzle within the gas and oil chamber adapted to discharge at a point to effect admixture of the oil, gas and steam within the device, the steam supply nozzle having a jet device discharging 90 slightly beyond the point of discharge of the gas and oil supply into the gas and oil chamber.
5. In a device of the character described, 95 a combined oil and gas burner comprising an outer member having a controlled inlet leading to an air chamber therewithin, a member constituting a gas and oil chamber within said air chamber arranged to discharge into a space within the device for admixture of the oil, gas and air, separate inlets for oil and gas passed through the outer member and into the member forming the gas and oil chamber so as to discharge 100 into the latter, and a steam supply nozzle within the gas and oil chamber adapted to discharge at a point to effect admixture of the oil, gas and steam within the device, the steam supply nozzle having a jet device discharging 105 slightly beyond the point of discharge of the gas and oil supply into the gas and oil chamber.
6. In a device of the character described, 110 a combined oil and gas burner comprising an outer member having a controlled inlet leading to an air chamber therewithin, a member constituting a gas and oil chamber within said air chamber arranged to discharge into a space within the device for admixture of the oil, gas and air, separate inlets for oil and gas passed through the outer member and into the member forming the gas and oil chamber so as to discharge 115 into the latter, and a steam supply nozzle within the gas and oil chamber adapted to discharge at a point to effect admixture of the oil, gas and steam within the device, the steam supply nozzle having a jet device discharging 120 slightly beyond the point of discharge of the gas and oil supply into the gas and oil chamber, and said jet device flaring outwardly to form a restricted annular passage for the oil and gas to the space within which the steam mixes therewith.
7. In a device of the character described, 125 a combined oil and gas burner comprising an outer member having a controlled inlet leading to an air chamber therewithin, a member constituting a gas and oil chamber within said air chamber arranged to discharge into a space within the device for 130

admixture of the oil, gas and air, separate inlets for oil and gas passed through the outer member and into the member forming the gas and oil chamber so as to discharge 5 into the latter, and a steam supply nozzle within the gas and oil chamber adapted to discharge at a point to effect admixture of the oil, gas and steam within the device, the end of the oil and gas chamber beyond the 10 point of admixture of the steam, oil and gas being restricted to provide a jet discharge into the space where the mixture of the oil, gas and steam mixes with the air.

7. In a device of the character described, 15 a combined oil and gas burner comprising an outer member having a controlled inlet leading to an air chamber therewithin, a member constituting a gas and oil chamber within said air chamber arranged to discharge 20 into a space within the device for admixture of the oil, gas and air, separate inlets for oil and gas passed through the outer member and into the member forming the gas and oil chamber so as to discharge into the latter, and a steam supply nozzle within the gas and oil chamber adapted to discharge at a point to effect admixture of the oil, gas and steam within the device, the steam supply 25 nozzle having an adjustable supporting portion enabling different positioning of the 30

steam inlet means communicating with the said nozzle.

8. In a device of the character described, a combined oil and gas burner comprising 35 an outer member having a controlled inlet leading to an air chamber therewithin, a member constituting a gas and oil chamber within said air chamber arranged to discharge into a space within the device for admixture of the oil, gas and air, separate 40 inlets for oil and gas passed through the outer member and into the member forming the gas and oil chamber so as to discharge into the latter, and a steam supply nozzle within the gas and oil chamber adapted to 45 discharge at a point to effect admixture of the oil, gas and steam within the device, the steam supply nozzle having a supporting member at one end of the device having a hollow interior alined with said nozzle, and 50 a removable closure affording access to said hollow interior and steam supply nozzle.

In testimony whereof we hereunto affix our signatures in the presence of two witnesses.
